Attorney

UNITED STATES PATENT OFFICE.

LOUIS V. BARACH, OF PITTSBURGH, PENNSYLVANIA.

BUFFER DEVICE FOR BILLIARD CUES.

Application filed May 25, 1923. Serial No. 641,383.

To all whom it may concern:

Be it known that I, LOUIS V. BARACH, a citizen of the United States, residing at Pittsburgh, in the county of Allegheny and 5 State of Pennsylvania, have invented certain new and useful Improvements in Buffer Devices for Billiard Cues, of which the following is a specification.

This invention relates to a buffer device 10 adapted to be attached to the handle end of a billiard cue, and while primarily designed for use in connection with a billiard cue, it will be obvious that the device may be successfully employed in connection with various appliances wherein it is found to be applicable.

The primary object of this invention is to provide a device of the character stated, which will mitigate the annoyance caused 20 by the noise due to the prevalent habit of players of thumping the butt end of their cues upon the floor between shots, and further to protect the butt end of the cue from injury due to impact of such thumping action.

Further objects of the invention are to provide a device of the class stated, in a manner as hereinafter set forth, which may be readily attached to the butt end of any 30 billiard cue of conventional construction, which is simple in its construction and arrangement, strong, durable, and efficient in its use, attractive in appearance and comparatively inexpensive to manufacture.

To the accomplishment of these and such other objects as may hereinafter appear, the invention consists of the novel construction and arrangement of parts herein specifically described and illustrated in the accompanying drawing wherein is shown an embodiment of the invention, but it is to be understood that the device shown is merely illustrative of what is now thought to be the best embodiment thereof, and that various 45 changes in the form, proportion and minor details of construction may be resorted to, without departing from the principle or sacrificing any of the advantages of the invention, which come within the scope of the 50 claims hereunto appended.

In the drawing forming a portion of this specification and wherein like numerals of reference designate corresponding parts throughout the several views:

Figure 1 is a vertical sectional view of

my improved buffer device attached to a billiard cue, a portion of the latter being broken away.

Figure 2 is a top plan view of the buffer member.

Figure 3 is a side elevation thereof.

Figure 4 is a top plan view of the cap member.

Figure 5 is a side elevation thereof.

Referring in detail to the drawing 1 denotes the butt end of a billiard cue, comprising a hollow metal body portion 2 enclosed in a casing 3 preferably constructed from bakelite or other suitable composition material capable of being molded around the metal body portion 2 and formed to provide a tapering cue of regulation contour. The metal body portion 2 is formed with an externally threaded lower end 4 which projects beyond the lower end of the casing 3. 75 The setting up of the casing 3 and body portion 2, in the manner as stated, provides the cue with a peripherally threaded reduced lower end terminal portion and a shoulder at the upper terminus of the latter.

A metal cap 5, formed with a threaded inner wall 6, is mounted on the threaded lower end 4 of the metal body portion 2. The bottom of the cap 5, is provided with a large centrally disposed aperture 7, adapted for the passage of the buffer member 8 therethrough as clearly shown in Figure 1, of the drawing. The outer diameter of the cap 5 is such as to form an uninterrupted symmetrical continuity, relatively to the periphery of the casing 3.

The buffer member 8 is constructed from rubber and is formed at its inner end with a laterally disposed annular flange 9 which is clamped between the inner face of the cap bottom and the terminus of the metal body portion 2 for securing the buffer member 8 in position.

In the use of my improved buffer device in connection with a cue, the butt end of the latter is rendered noiseless when thumped upon the floor by the player. The buffer device will further protect the cue butt against injury due to the impact of such thumping action. When the buffer device is attached to a cue having a hollow body portion of the construction herein described, the resiliency of the buffer member 8 is appreciably augmented, as the inner end of the latter is engaged only by the flange 9 and

is not fully seated against the cue butt as when used in connection with a cue of the ordinary solid construction.

What I claim is:—

5. 1. The combination with an inner hollow metallic cue section open at its butt end, and an outer nonmetallic cue section enclosing and having its lower end terminating at a point removed from the edge 10 of the butt end of the inner section, that portion of the inner section extended from the outer provided throughout with peripheral threads, of a solid resilient cylindrical body having its upper end provided with a laterally extending annular flange of substantial thickness seated against the edge and of the same diameter as the outer diameter of said inner section at the butt end thereof, and an interiorly threaded cap 15 threadably engaging said threaded periphery throughout and provided at its lower end with an inwardly extending annular flange seating against the lower face of the flange of said element for coupling the latter to said inner section.

2. The combination with an inner hollow metallic cue section open at its butt end, and an outer non-metallic cue section enclosing and having its lower end terminating at a point removed from the edge 30 of the butt end of the inner section, that portion of the inner section extended from the outer provided with peripheral threads, of a solid resilient cylindrical body having its upper end provided with a laterally extending annular flange of substantial thickness seated against the edge and of the same diameter as the outer diameter of said inner section 35 at the butt end thereof, and an interiorly threaded cap threadably engaging said threaded periphery and provided at its lower end with an inwardly extending annular flange seating against the lower face of the flange of said element for coupling the latter to said inner section.

45 3. The combination with an inner hollow metallic cue section open at its butt end, and

an outer non-metallic cue section enclosing and having its lower end terminating at a point removed from the edge of the butt end 50 of the inner section, that portion of the inner section extended from the outer provided throughout with peripheral threads, of a solid resilient cylindrical body having its upper end provided with a laterally extending annular flange of substantial thickness seated against the edge and of the same diameter as the outer diameter of said inner section at the butt end thereof, and an interiorly threaded cap 55 threadably engaging said threaded periphery throughout and provided at its lower end with an inwardly extending annular flange seating against the lower face of the flange of said element for coupling the latter to said inner section, 60 said cap abutting against and having its outer diameter the same as the outer diameter of the outer section.

4. The combination with an inner hollow metallic cue section open at its butt end, 70 and an outer non-metallic cue section enclosing and having its lower end terminating at a point removed from the edge of the butt end of the inner section, that portion of the inner section extended from the outer provided with peripheral threads, of a solid resilient cylindrical body having its upper end provided with a laterally extending annular flange of substantial thickness seated against the edge and of the same diameter 75 as the outer diameter of said inner section at the butt end thereof, and an interiorly threaded cap threadably engaging said threaded periphery and provided at its lower end with an inwardly extending annular flange seating against the lower face of the flange of said element for coupling the latter to said inner section, said cap abutting against and having its outer diameter the same as the outer diameter of the 80 outer section.

In testimony whereof I affix my signature.

LOUIS V. BARACH.
